Patented June 10, 1969

214,367

COMBINED OFFICE BUILDING STRUCTURE AND STANDPIPE

Howard D. Mills, Jr., Middletown, N.Y., and Thomas
A. Federico, Passaic, N.J., assignors to Mills Heights,
Inc., Middletown, N.Y., a corporation of New York

Filed Aug. 26, 1968, Ser. No. 13,268

Term of patent 14 years

Int. Cl. D26—04

U.S. Cl. D13—1

Fig. 1.

Fig. 2.

Fig. 3.

Fig. 4.

FIGURE 1 is a top plan view of a combined office building structure and standpipe showing our new design;

FIG. 2 is a front elevational view;

FIG. 3 is a side elevational view; and

FIG. 4 is a view taken along the lines 4—4 of FIG. 1 and looking in the direction of the arrows with the standpipe being shown in full elevation and the surrounding building structure being shown in cross-section.

We claim:

The ornamental design for a combined office building structure and standpipe, substantially as shown and described.
